FRANK G. FREESE, OF ALDAN, AND RUSSELL C. PAXSON, OF LLANERCH, PENNSYLVANIA.

RAIL ANCHOR.

Application filed April 27, 1928. Serial No. 273,375.

Our invention relates to rail anchors, and comprises certain improvements in the type of anchors which are mounted in clamping engagement with the base flanges of a rail and cooperate with the ties to prevent creeping of the rail.

An important object of our invention is to provide an anchor having walls in positive engagement with the edge of each base flange 10 of a rail.

A further object of our invention is to provide an anchor made up of a series of curved webs or walls avoiding sharp angles; such curved portions permitting slight flexure 15 to insure clamping engagement with the base flanges of a rail upon the insertion of a key between a portion of the anchor and the base of the rail.

And a still further object of our invention 20 is to provide a portion of the web of the anchor with a slight concavity to serve as a guide for the key.

These and other features of our invention 25 are more fully described hereinafter; reference being had to the accompanying drawings, in which:

Figure 1 is a cross-sectional view of a conventional rail showing our improved rail anchor in position for application thereto; different positions assumed during application 30 being indicated.

Fig. 2 is a similar view, showing the anchor in operative position with respect to the base flanges of a rail; the full lines showing the 35 position before, and the broken lines the position after, the insertion of the key.

Fig. 3 is a similar view, showing the anchor in clamped position, with a locking key interposed between a portion of the same and 40 the base of the rail; said locking key serving to partially flex the body of the anchor and impart sufficient tension to maintain the same in clamped position.

Figs. 4 and 4^a are sectional views taken on 45 the line IV—IV, Fig. 3, looking in the direction of the arrows *b* and *b'*, respectively, and

Fig. 5 is a perspective view of the anchor 50 detached from the rail.

Our improved anchor comprises a section of metal of substantially uniform thickness, and of the shape or contour illustrated in the drawings, which shape may be referred to as follows:

The ends of our improved anchor are provided with overhanging lips or flanges 1 and 2, adapted to overlie the edges *a* and *a'* of the respective base flanges of a rail A, when in the operative position, as clearly indicated in Figs. 2 and 3. Below these flanges, short walls 3 and 4, substantially vertical, are provided, from which extend the curved portions 5 and 6, connected to a portion 7, substantially centrally disposed with respect to said portions 5 and 6. The portion 7 may be disposed in a substantially horizontal plane which may be parallel to the underside of the rail base, and this is the position when the key is in place, as indicated in Fig. 3. Preferably, the upper surface of the portion 7 is slightly inclined, as indicated by the full line position, Fig. 2. The curved portion 5 at what may be termed the front of the anchor comes forwardly so as to give sufficient space permitting application to the rail; the relatively long wall permitting flexure. The curved wall 6 also extends in the same general direction and its relation to the wall 4 is such as to provide a seat 4^a for the edge *a'* of the base flange between such curved portion 6 and the substantially vertical portion 4.

The anchor is held in clamping position with respect to the base flanges of the rail A by the application of a key 8, which may be passed through an aperture 9 formed in the curved wall portion 5 of the anchor; such key being forced to its seat between the portion 7 of the anchor and the underside of the rail base. This action flexes the walls of the anchor and sets up sufficient tension to hold the key in place and maintain the anchor in clamping position with respect to the base flanges of the rail.

By preference, the flange or lip 1 has line engagement with the base flange *a*, as indicated at *x*, and the flange or lip 2 may be similarly arranged if desired. The portion 7, between the curved portions 5 and 6, may be hollowed out slightly, as indicated at 7^a in Figs. 4 and 4^a, to serve as guiding means for the key when the latter is introduced for the purpose of clamping the anchor to the rail. An ordinary railroad spike may be employed as the key.

By having the walls 3 and 4 of the anchor in engagement with edges of the base flanges 105 and with a seat such as indicated at 4^a for one

of said flanges, that indicated at a' , between the lip 2 and the curved portion 6, the anchor is prevented from displacement; there being no opportunity for endwise movement after 5 the key has been finally seated.

We claim:

1. A rail anchor comprising a body of resilient metal extending transversely of a rail beneath the same and adapted to embrace the 10 flanges thereof; said anchor having substantially vertical end walls arranged for engagement with the edges of said rail flanges and curved portions continuous with said end walls and joining a substantially straight intermediate portion below said base flanges; one of said curved portions having an aperture below an end wall for the insertion of a key between the bottom surface of the rail base and the upper surface of the intermediate portion of said anchor to flex the body of said anchor into clamping engagement with the base flanges of a rail.

2. A rail anchor comprising a body of resilient metal extending transversely of a rail beneath the same and adapted to embrace the flanges thereof; said anchor having substantially vertical end walls arranged for engagement with the edges of said rail flanges and curved portions continuous with said end walls and joining a substantially straight and slightly inclined intermediate portion below said base flanges; one of said curved portions having an aperture below an end wall for the insertion of a key between the bottom surface of the rail base and the upper surface of the intermediate portion of said anchor to flex the body of said anchor into clamping engagement with the base flanges of a rail.

3. A rail anchor comprising a resilient member adapted to embrace the base flanges of a rail and having a pair of inwardly turned lips at its ends, a vertical portion adjacent each of said lips, curved portions continuous with and extending from said vertical portions toward each other and joining an intermediate straight portion disposed above the plane of the lowermost parts of said curved portions and extending transversely of the rail; one of said vertical walls being apertured for the insertion of a key between the bottom of the rail base and said

intermediate portion to flex the anchor into clamping engagement with a rail base.

4. A rail anchor comprising a resilient member adapted to embrace the base flanges of a rail having a pair of inwardly turned lips at its ends, a vertical portion adjacent each of said lips, curved portions continuous with and extending from said vertical portions toward each other and joining an intermediate straight portion disposed above the plane of the lowermost parts of said curved portions and extending transversely of the rail; one of said vertical walls joining the curved wall in such manner as to provide a seat for the edge of one of the base flanges and the other curved wall being apertured for the insertion of a key between the bottom of the rail base and said intermediate portion to flex the anchor into clamping engagement with a rail base.

5. A rail anchor comprising a resilient member having inwardly turned terminal lips joined by an intermediate section made up of vertical-walled sections adjacent said lips, curved sections, and a section substantially straight underlying the base of the rail; said curved sections being adapted to flex under the pressure exerted by a key driven transversely of the rail between the bottom thereof and the intermediate portion of the anchor and said intermediate portion being slightly grooved to guide the key.

6. A rail anchor comprising a resilient member having terminals with substantially vertical walls and inturned lips or flanges adapted to overlie the base flanges of a rail and a connecting portion for said end walls comprising curved portions connected by a substantially straight web portion underlying the base of the rail, in combination with a key adapted to be driven transversely of the rail between the bottom thereof and the web portion underlying the rail base; said web portion being substantially horizontal and parallel with the underside of the rail base when the key is in position.

In witness whereof we have signed this 100 specification.

FRANK G. FREESE.
